UNITED STATES PATENT OFFICE

CLINTON H. SAWYER, OF NEW YORK, N. Y.

APPARATUS FOR MAKING COLUMNS AND THE LIKE

Application filed March 14, 1930. Serial No. 435,829.

This invention relates to the making of columns of straight, tapered, or entasis form; and it is the object of the invention to provide an improved apparatus for reducing the size of tubes or sections of arcuate shape in cross-section to smaller size of either straight, tapered, or entasis form for use as flagpoles, masts, booms, spars, and the like.

It is a further object of the invention to provide an improved die embodying adjustable members to shape or draw tubing to reduced sizes and different shapes.

In carrying out the invention there is provided a supporting structure embodying parallel and spaced sills, a die carrier and support for the column to be shaped or formed being mounted upon and suspended between said sills and relative to which a column as it is formed is moved by a carriage mounted to travel upon the supporting sills. The die embodies a series of sectors disposed about and pivotally supported on the carrier at the vertex to have adjustment in the plane of and toward and away from the axis of the carrier. The curved end of the sectors is in an arc eccentric to the axis and of arcuate shape in cross-section and progressively narrowed from one end to the opposite end, each forming a segment of a circular die which is decreased in size by the adjustment of the sectors in one direction and increased when the sectors are adjusted in the opposite direction. Means are provided to adjust the die members to variably decrease or increase

the passage between the members, means also being provided to effect automatic adjustment of the die members by the movement of the column through the die in the forming thereof, which adjustment is proportional to the travel of the column to produce a column progressively narrowed toward the end.

In the drawings accompanying and forming a part of this application Figure 1 is a cross-sectional view, on an enlarged scale, taken on the line 1—1 of Figure 2 looking in the direction of the arrows and at the end of the die;

Figure 2 is a side elevation with a support-

ing sill removed to illustrate the operative parts;

Figures 3 and 4 are side and end elevations, respectively, of the die-carrying head;

Figures 5 and 6 are front and side elevations, respectively, of the actuator for the die-adjusting means mounted on the die-carrying head;

Figures 7 and 8 are side and end elevations, respectively, of a die member;

Figure 9 is a perspective view of a column or tube arranged preparatory to forming it to tapered entasis form by drawing or passing the tube through the die and Fig. 10 shows the finished product.

In the embodiment of the invention illustrated the supporting structure comprises a pair of parallel and laterally spaced sills or I-beams 9 mounted upon blocks S, preferably of concrete, spaced longitudinally of the sills. A die carrier is suspended in interposed relation between the sills at a point intermediate the ends thereof by a supporting bracket 10 fixed upon and extending between the sills. This die carrier (Figures 3 and 4) embodies a tubular head portion 11 with the outer contour of rectangular shape in cross-section, and having pairs of parallelly and laterally spaced ears 12 extended beyond one end and laterally of the tubular portion with one ear of each pair of ears arranged at a right angle to an ear of another pair of ears, as clearly shown in Figure 4.

The die comprises a series of members 13 of sector shape, shown in the present instance as four in number, the curved side or end 14 of which sectors is arranged eccentric to the center on the axis of the sectors and having a groove 15 in the face thereof of arcuate shape in cross-section and progressively narrowed or tapered from the one end 15^a to the opposite end 15^b. These sectors are pivotally supported at the vertex between the pairs of ears 12 by pins 16 engaged in perforations 17 in the ears with the curved end 14 extending and adapted to have movement in the plane of the axis of the die-carrying head 11, the arcuate faces of the curved ends being disposed about the axis of the die-car-

rying head to constitute segments of the die and the space between said faces constituting the opening through the die.

By the arranging of the curved end 14 eccentric to the axis 16 of the sectors the space or opening between said faces will be of greater extent when the sectors are adjusted to the position shown in Figure 2 with the larger end of the arcuate recess 15^a in said 5 faces opposed to each other, and as the sectors are moved or adjusted to position the smaller end of the arcuate recess 15^b in the faces in opposed relation to each other said space will be diminished and the arcuate 10 faces constitute a segment of a circle conforming to such diminished size. It will be obvious that by the gradual movement of the sectors that the space between the sectors will be gradually diminished and the arc of the 15 segment will be correspondingly diminished. 20

The sectors are simultaneously adjusted by racks 18, there being four in number equal to the number of the sectors, mounted to have longitudinal sliding movement in recesses 19 25 in the outer surface of the die-carrying head 11 adjacent to the base of an ear of each pair of ears 12. These racks mesh with gears 20 mounted on the pins 16 concentric of the pivot support of the sectors and connected thereto whereby the gears and sectors will have participating movement. The gears and sectors may be attached to each other and loosely mounted on the pins 16, or they may be fixed to the pins 16 and the latter 30 rotatably mounted in the perforations of ears 12. To adjust the racks and thereby the sectors through the gears simultaneously the racks are connected to an actuator in the form of a collar 21 shaped to conform to the 35 exterior cross-sectional shape of the head-carrying die and slidably mounted thereon, the inner wall of the collar having recesses 21' therein for the engagement and securing of the racks 18 therein. It will be obvious 40 that should the rack actuator 21 be adjusted on the die-carrying head to the right from the position shown in Figure 2 that the sectors will be adjusted in the direction of movement of the rack actuator, and that the 45 curved ends 14 of the sectors will be moved in the plane and toward the axis of the die-carrying head, and when the rack actuator is adjusted in the opposite direction the sectors will be moved in the plane of and away 50 from the axis of the die-carrying head. To reduce a column such as a tube or circular stock A to a smaller diameter the die sectors are adjusted to accommodate the size of the work. The work is drawn through or 55 between the die sectors by engaging the end between the legs of a bifurcated portion 22 of a carriage C suspended between the supporting sills upon which the carriage is mounted to travel along the same, the work 60 being connected with the carriage by a pin

23 extended through perforations in the bifurcation legs and a hole formed in the work. The carriage is connected to power means (not shown) by a cable or draw-bar 24. As the work is drawn between the die members 70 they are adjusted by the adjustment of the rack actuator on the die-carrying head until the work assumes the desired cross-sectional shape.

In the method of forming a tubular column of the same diameter throughout to tapered and entasis form, portions of the tube or column are first removed to provide tapered slots extended through one end and toward the opposite end by a milling cutter 75 of suitable structure operating from one end of the tube toward the other end and being progressively withdrawn laterally from the tube to form the converging walls, as shown 80 at 25 in Figure 9, the tube in the present instance being arranged with two of such slots arranged diametrically opposite, although it may be provided with a greater number of slots, which may be desirable depending 85 upon the diameter of the column or tube to be reduced. By so slotting the tube or column 90 the portions *a* between the slots are of progressively reduced width from the apices 95 of the slots to the end. To shape the slotted column or tube to tapered entasis form 100 the unslotted end portion 26 of the column is engaged between the die members and attached to the carriage as hereinbefore described and as shown in Figure 2, when the 105 column or work is drawn between the die members. To shape the slotted portion of the column to progressively reduced or tapered and entasis form means are provided operative from the travel of the carriage along the supporting sills to adjust the die 110 members proportionally to the travel or movement of the column to effect a decrease in the space between the die members. This is effected by adjusting the rack actuator 21 through a templet or bar 27 having a cam 115 edge 27' conforming to the desired shape or entasis to which the column is to be shaped, said templet bar being supported to have longitudinal sliding movement and connected with the carriage C, as at 28, to participate in 120 the movement of the column or tube A.

To operatively connect and adjust the rack actuator 21 from the templet bar a follower in the form of a flanged roller 29 engages and follows the cam edge of the templet, said 125 roller being rotatably carried on a headed stud 30 secured in a carrier 31 pivotally supported at one end from an arm 32 mounted on a shaft 33 supported at the ends in bearings 34 fixed upon the supporting sills 9. The opposite end of the roller carrier 31 is pivotally connected to an arm 35 fixed on a shaft 36 rotatably supported at the ends in hangers 37 fixed to or forming a part 130 of and extended downward from the bear- 135

ings 34, said hangers being also supported intermediate the ends by the supporting sills by tie members 38 and spaced from the sills by spacers 39, the hanger at the right as viewed in Figure 1 also carrying a support 40 for the templet 27. The shaft 36 is in the nature of a rock shaft and is connected with the rack actuator 21 by a pair of arms 41 fixed on said shaft and extending upward therefrom and connected with the rack actuator by links 42 pivotally connected to opposite sides of the rack actuator, as at 43. The parts are shown at the commencement of the operation of progressively narrowing the 15 column or shaping it to tapered form in Figure 2, in which position the templet follower 29 is at the commencement of the cam edge 27' of the templet. As the column is drawn between the die members and the 20 follower rides upon the templet cam edge the follower carrier 31 will be raised or moved transversely to the longitudinal movement of the templet thereby rocking the shaft 36 and the arms 41 and through the 25 link connection 42 of the latter with the rack actuator 21 move said rack actuator to the right as viewed in Figure 2, and thus adjusting the die members to reduce the space between the faces of said die members, and 30 effecting a shaping of the portions *a* of the column between the slots 25 to arcuate form in cross-section and the arc extending through substantially 180 degrees, and simultaneously therewith bringing the edges 35 *b*, *c* of said sections or the walls of the slots into abutting relation, not only gradually lengthwise diminishing the cross-sectional area of the column but also maintaining it in circular shape and of entasis form. After 40 the column has been so shaped the abutting walls are welded together, as by electric welding, which may be done simultaneously with the forming of the column as it is drawn between the die sectors.

45 The tubing which is reduced in cross-section and progressively narrowed from one end of the opposite end is of stock size, and should the length of the desired flagpole, mast, boom or spar come within such stock 50 length only one section of tube length is required. However, should the length of the flagpole, mast, boom or spar be required to be of a length greater than a stock size then successive sections of tubing are reduced in 55 cross-section and the sections united in an endwise relation, the successive sections being progressively narrowed to smaller size and united with the end of larger cross-section of successive sections in abutting relation to the smaller end of the adjacent section.

60 If desired the stock to start from may comprise two sections of like arcuate shape in cross-section with the arc at one end extending through 180 degrees so that the longi-

tudinal edges of one section at one end may be brought into abutting relation with the longitudinal edges at one end of the other section, as shown for illustrative purposes by dot and dash lines 25^a in Figure 9, and 70 form a tubular portion at one end, which end constitutes the starting end in the method of reducing the plates so formed to tubular shape and progressively narrowed from one end to the opposite end, said ends with the longitudinal edges of one plate in abutting relation to the longitudinal edges of the other plate, as indicated by dot and dash line 25^a, being positioned between the faces 14 of 75 the die sectors 13 preparatory to the drawing of the tube sections through the die in the reducing of the same.

80 While I have illustrated and described one embodiment of apparatus for carrying out the method it will be obvious that various modifications may be made in construction and arrangement of parts without departing from the scope of the invention, and that portions may be used without others and come within the scope of the invention.

90 Having thus described my invention I claim:

1. In apparatus for reducing round metal stock to smaller diameter, a die embodying a series of members each having the face of 95 arcuate shape in cross-section, a head on which said die members are pivotally mounted to have adjustment toward and away from the axis of the head, said members being circumferentially disposed about the axis of the head and the arcuate faces constituting segments of the die opening, and means to adjust said die members to increase and decrease the space between the faces of said members.

100 105 110 115 120 125 130

2. In apparatus for forming tapered columns, a die embodying a series of sectors, each sector having the curved face arranged of arcuate shape in cross-section, a head upon which the sectors are pivotally mounted at the vertex to have movement on an axis transverse of the sector and in the plane of the axis of the support with the arcuate face of each sector forming a segment of a circle, and means to simultaneously adjust said sectors.

3. Apparatus for forming tapered columns as claimed in claim 2, wherein the arcuate face of the sectors progressively narrows from one end to the opposite end and is arranged eccentric to the pivotal support of the sector upon the head, whereby as the sectors are adjusted in one direction the space between the sectors is progressively decreased and when adjusted in the opposite direction progressively increased.

4. Apparatus for forming tapered columns as claimed in claim 2, wherein the means to adjust the sectors comprises gears concentric of the pivotal support of and mov-

able with the sectors, and racks carried by the sector-carrying head to have longitudinal adjustment meshing with the gears.

5. Apparatus for forming tapered columns as claimed in claim 2, wherein the arcuate face of the sectors progressively narrows from one end to the opposite end and is arranged eccentric to the pivotal support of the sectors, and the means to adjust the sectors comprising gears arranged concentric of the pivotal support of and movable with the sectors, racks meshing with said gears slidably carried by the head, and an actuator to which said racks are fixed slidable on the head.

6. Apparatus for forming tapered columns as claimed in claim 2 wherein the sector-carrying head comprises a tubular member arranged with pairs of spaced and parallel ears extended beyond one end of and laterally from the tubular member and the arcuate faces of the sectors by the adjustment of the sectors adapted to be positioned beyond the tubular wall of the head.

7. In apparatus for forming tapered columns, a supporting structure embodying spaced and parallel sills, a die carrier and column support carried by and suspended between said sills, sector-shaped die members having the curved ends arranged eccentric to the axis of the sectors with the face of said ends of arcuate shape in cross-section and progressively narrowed from one end to the opposite end, said sectors being disposed about and pivotally mounted at the vertex upon the die carrier with the curved faces to extend in the plane of the axis of the carrier and adapted to be adjusted to have movement in the plane and toward the axis of the carrier, means to actuate and effect adjustment of said die members, and means to draw a column as it is formed relative to the column support and between said die members and effect adjustment of the die members toward the axis of the die carrier in predetermined ratio to the longitudinal movement of the column.

8. Apparatus for forming tapered columns as claimed in claim 7, wherein the means to draw the column relative to the die members comprises a carriage mounted to travel on the sills and arranged with means suspended between the sills for connection with the column, and a templet bar slidably supported to extend parallelly of the column and have longitudinal movement, said templet bar being connected with the carriage to participate in the movement of the column and effect actuation of the means to adjust the die members.

9. Apparatus for forming tapered columns as claimed in claim 7, wherein the means to effect adjustment of the die members comprises gears rotatable on the axis of the support for and connected with the die members,

racks slidably mounted on the die carrier meshing with the gears, and an actuator to which the racks are connected slidable on the die carrier.

10. Apparatus for forming tapered columns as claimed in claim 7, wherein the means to effect adjustment of the die members comprises gears rotatable on the axis of and connected with the die members, racks slidably mounted on the die carrier meshing with the gears, a collar to which the racks are connected slidable on the die carrier to effect adjustment of the racks and thereby of the die members, a longitudinally movable templet bar connected with the carriage to participate in the movement of the column and having an operative connection with and effecting adjustment of the rack-carrying collar and racks and thereby adjustment of the die members.

11. Apparatus for forming tapered columns as claimed in claim 7, wherein the means to effect adjustment of the die members comprises gears connected with the die members concentric of the pivotal support thereof, racks meshing with said gears slidably mounted on the die carrier, a carrier for said racks slidable on the die carrier to effect longitudinal adjustment of the racks, a templet bar slidably supported to have longitudinal movement and connected with the carriage to participate in the column advancing movement thereof, a templet follower, a pivoted support for said follower to have movement in a direction transversely of the movement of the templet by the travel of the templet relative to said follower, said support having an operative connection with and transmitting the movement thereof to the rack carrier and thereby effect adjustment of the die members.

12. Apparatus for forming tapered columns as claimed in claim 7, wherein the means to effect adjustment of the die members comprises gears connected with the die members concentric of the pivotal support thereof, racks meshing with said gears slidably mounted on the die carrier, a carrier for said racks slidable on the die carrier to effect longitudinal adjustment of the racks, a templet bar slidably supported to have longitudinal movement and connected with the carriage to participate in the column advancing movement thereof, and means actuated from the templet by the travel thereof to effect adjustment of the rack carrier and thereby adjustment of the die members.

13. Apparatus for forming tapered columns as claimed in claim 7, wherein the means to effect adjustment of the die members comprises gears connected with the die members concentric of the pivotal support thereof, racks meshing with said gears slidably mounted on the die carrier, a carrier for said racks slidable on the die carrier to effect

longitudinal adjustment of the racks, a templet bar slidably supported to have longitudinal movement and connected with the carriage to participate in the column advancing movement thereof, a templet following roller, a carrier for said roller, a pivoted support for said roller carrier to permit movement thereof transversely of the travel of the templet, and an arm participating in the movement of said roller carrier support having a link connection with the rack carrier to transmit the movement of the roller carrier to and effect adjustment of the rack carrier and thereby of the die members.

Signed at the city of New York, in the county of New York and State of New York, this 21st day of February, A. D. 1930.
